LAST

Henry L. Moorhouse, Brockton, Mass., assignor
to Brockton Last Company, Brockton, Mass., a
corporation of Massachusetts

Application January 20, 1933, Serial No. 652,629

1 Claim. (Cl. 12—133)

My present invention is a novel and improved form of last for use in the manufacture of boots and shoes, preferably in accordance with the method as explained and claimed in my co-pending application, Ser. No. 644,210, filed November 25, 1932, on Method of making boots and shoes, shoe pattern therefor, and boot made thereby.

My present form of last is capable and suitable for embodiment either in a block or solid last, hinged last of any desired type, or any other two-part or three-part divisible last construction, the main and principal elements of importance and novelty consisting in the design of same, particularly the position, location, and contour of the cone portion of the forepart.

Heretofore in last constructions it has been customary to design lasts for various purposes by constructing the longitudinal lines of the last with relation to the center line from the extreme heel to the extreme toe portions. Various methods of designing a last with relation to such a center line have been attempted, particularly in drafting lasts for special orthopedic shoes.

In my present invention, however, I have disregarded such a longitudinal alignment in the last designs and, on the contrary, have discovered that a last, and consequently the shoe made thereon, which is entirely disaligned from the usual longitudinal axis or center of the last is much more closely fitting to the natural and normal foot than that of any prior structure.

In carrying out my invention, therefore, I have so drawn, designed, and constructed my present improved shoe last as to direct the contour of the forepart from the top or cone downwardly to the ball of the foot at a direction inwardly toward the arch portion, viz., to the left on a right last, and to the right on a left last. This novel feature allows a more nearly vertical or perpendicular face or surface to the last and, hence to the shoe made thereon, directly above the arch portion and greatly facilitates the closer fitting of the resultant shoe upper, both from the arch side, drawing up the leather snugly to the last and, hence, to the foot as well as to the opposite side where the upper materials are so cut and formed as to draw across the central front portion of the foot, all as explained in my said copending application directed to claim the improved method, shoe pattern made therefor, and the shoe structure made thereby.

Referring to the drawing, illustrating a preferred embodiment of my invention,

Fig. 1 is a plan view of the last for a right shoe;

Fig. 2 being a vertical plan view;
Fig. 3 is a cross-sectional view on the line 3—3 of Fig. 2, and

Fig. 4 is a cross-sectional view on the line 4—4 of Fig. 2.

As shown in the drawing, wherein a typical form of hinge last is illustrated, 1 is the forepart, 2 the heel part united by any suitable or desirable hinge last structure and of any desired size or style, the last here illustrated being a typical standard form for a man's shoe. From the top of the cone 3, the contour of the last—instead of following a substantially straight line as usual in alignment with the axis of the shoe to the toe portion, is formed at a pronounced angle to the left, as shown in Fig. 1 of the right shoe, and correspondingly to the right in a left shoe, the arch of the cone or contour extending approximately as shown from the point 3 to a suitable point 5 in the forepart, where the conical ridge of the last merges into the forepart. This construction, with the resultant lacing opening in the shoe, made thereon following the contour from 3 to 5 gives a substantially vertical portion 6 along the side of the arch to the cone from 3 to 5 and a consequently much larger proportion for the outer surface, as indicated at 10, from the outer edge of the sole of the resultant shoe to the approximate position of the lacing opening in the shoe, also as more fully explained in my said copending application.

I believe that my novel and improved last, as thus described, with the contour of the forward cone portion from the position substantially as shown at 3 to approximately the point 5, viz. from top to forepart with the same disaligned and at the extreme side of the center line of the last substantially as shown, is a distinct novelty in the art of last manufacture and in the consequent art of shoe manufacture, and I wish to claim this feature broadly.

I claim:

A wooden last for use in the manufacture of boots and shoes, having a heel portion substantially symmetrical with regard to the longitudinal axis of the last, in combination with a forepart having the extreme forward conical contour of the topmost ridge portion disaligned both from the heel and the longitudinal axis of the last, said disaligned ridge portion extending into the toe portion forwardly of the ball of the last, said forwardly extending disaligned ridge portion being in a relative position to produce a substantially vertical face from the cone to the arch of the last at the left of a right last, and at the right of a left last.

HENRY L. MOORHOUSE.
